UNITED STATES PATENT OFFICE.

JAMES E. EMERSON, OF BEAVER FALLS, PENNSYLVANIA.

MACHINE FOR MILLING RECESSES IN SAW-PLATES.

SPECIFICATION forming part of Letters Patent No. 315,753, dated April 14, 1885.

Application filed January 12, 1885. (No model.).

To all whom it may concern:

Be it known that I, JAMES E. EMERSON, a citizen of the United States, residing at Beaver Falls, in the county of Beaver, and State of Pennsylvania, have invented certain new and useful Improvements in Machines for Milling the Recesses in Saw-Plates to Receive Insertible Teeth, of which the following is a specification, reference being had to the accompanying drawings.

This invention relates to machines for milling or forming the ribs or grooves upon the inner edges of the recesses in saw-plates in which insertible and removable teeth and their holdings or fastenings are secured; and it consists in the construction of the machine, its parts, and their combinations to produce the effect desired.

In the drawings, Figure 1 represents a longitudinal sectional view of the machine on line $\alpha\alpha$ of Fig. 2. Fig. 2 represents a top or plan view of the machine. Fig. 3 represents a side view of the machine. Figs. 4 and 4' represent the device for clamping the saw-plate, a section of a saw, the pattern, and guide-pin of pantograph. Fig. 5 represents the guide-pin of the pantograph in sectional and detached view. Fig. 6 represents a side and sectional edge view of pattern. Fig. 7 represents the mandrel and its screw-nut for clamping or gripping the cutters and revolving them, and Fig. 8 represents a side view of a clamping-jaw enlarged.

A represents a saw-plate having its recesses a in the outer circumference of saw-plate.

B is a movable or sliding rest, upon and in the top of which is a sliding plate, B'. This plate B' has an upright screw-bolt, a', through it near its inner end, which bolt projects above the plate B' far enough and through the center hole in the saw to have a screw-nut, a'', to turn down upon the saw-plate A, and to hold it firmly in position while being operated upon to mill or form the angular or other form of rib in the recesses of the saw-plate. The sliding rest B is moved upon the frame or bed C by means of horizontal screw-rod b, having gear-wheel b' at its inner end gearing into gear-wheel b'' on a shaft, at the outer end of which is a hand-wheel, b''', and the outer end of screw-rod b works in the screw-cut hole

b^4 , as seen in Fig. 1, and by which construction any sized circular saw-plate can be held thereon and be presented to the cutters to be operated upon.

D represents a device for clamping the saw near its periphery to firmly hold it while a recess in the saw-plate is being acted upon to form the rib therein. Said device is attached to the frame or bed C, so as to be moved back and forth on the bed C, as seen in Fig. 4. This clamp is in two parts, D' and D'', each having a clamping-jaw, E, one jaw directly over the other. The upper jaw, fast to part D'', is adjustable toward or from the lower part, D', by means of screw-bolts e e, screw-nuts e' e', and wrench e''. When the screw-nuts e' are turned back, the clamping-jaws E are separated by the spiral springs e'''. The clamping-jaws E are secured to D' D'' by the screw-bolts e e, as seen in Fig. 4.

e' e'' is a guide attached to the clamping device, by which the distance to revolve the saw-plate from recess to recess is determined, and when arrested the saw-plate is then clamped, as is represented in Fig. 3, and in dotted lines in Fig. 4. When the clamps D' D'' are opened, the saw-plate is free to revolve about the center-pin a' on rest B, to present a new recess to be acted upon, where it is stopped by the jointed guide-stop e' e'' at the exact point necessary to cut the rib in the recess.

d d are the milling-cutters, made of the best of steel, are tapered at their ends—that is, smaller at their extreme ends than at their bodies—cylindrical in form, and their tapered ends grooved and made into sharp cutters to cut the tempered steel of a saw-plate. The cutting-edges of these cutters are made to be right and left on the opposite ends, so that when they are reversed the ends to be used in the cutting will have the edges of the teeth revolved to cut in the same direction in pairs. These cutters may be made in a single piece of steel, as shown in detail in Fig. 1; but I prefer to have them separate, because the teeth can be sharpened much better when separate, and are easier made than when in one piece of steel. Further, when the cutting-teeth are upon both ends of separate cutters, double the work can be done with them that

can be done when in a single piece, as when one end is dull it is then reversed. Cutters d are clamped in revolving and adjustable slotted holders or mandrels d' (which are moved 5 toward or from each other by temper-screws h^4 h^4) by means of a screw-nut, d'' , that is turned upon the tapering slotted end of holder d' , so that they can be removed and reversed as desired, and so arranged as that the meeting ends of the cutters will be in the exact center of the thickness of the saw-plate when at work.

F is an upright shaft, of suitable size and length, and having at the proper height universal joint f , with sufficient play to allow the lower end of the shaft to move out of an upright position in either direction, so as to allow the cutters d to traverse a recess in the saw-plate and cut the rib in the edges thereof. 15 The shaft F is put in revolution by coupling it with another vertical shaft, F' , which revolves in bearings $f' f'$ by a belt around a pulley, f'' , or other known means to produce the revolution of and the result by such revolution. 20

G is a sliding machine-head constructed to slide in the frame C on proper guideways, as seen in Figs. 2 and 3.

H is a sliding cross-head that reciprocates 30 transversely (on dovetail slides $h h$) to the direction of that of the sliding head G , and perpendicularly through this head H is the lower shaft, f''' , which is coupled to shaft F above the cross-head. To this shaft are attached, at 35 proper distances apart, the gear-wheels $g g$, that gear into two other gear-wheels, $g' g'$, which latter wheels are secured to the mandrels $d' d'$, that contain the cutters $d d$, that cause their revolution. By such construction the turning 40 of the pulley f'' will revolve the cutters d in the same direction simultaneously. Reciprocation is given to the sliding head G by turning hand-wheel h' by means of gear-wheel h'' and rack h''' .

45 To give a transverse movement to cross-head H , there is a hand-lever, I , having teeth at its inner end to gear into revolving wheel i , which gears into a rack, i' , that is fast to cross-head H , and attached to lever I is a spiral spring, 50 i'' , and to it a rod, i''' , and to this rod a thumb-piece, i'''' , having joint j , so that by taking hold of the handle end of lever I and pressing the thumb on the thumb-piece i'''' the lever will be drawn outward, so that the teeth 55 on its inner end will be out of gear with the wheel i , when the lever can be placed in the most desirable position. Then by pulling or pushing lever I the cross-head H can be moved in either direction or held at any place desired, and the operator with his other hand hold of wheel h' moves the sliding head G in a transverse or right-angled direction.

At the lower part of cross-head H is attached a pantograph steel guide-pin, J , Fig. 65 3, with its lower end pointed to about an angle of forty-five degrees, and to the bed of the

machine is attached an adjustable casting, j' , and upon this a hardened polished steel pattern, j'' , having the desired opening with beveled edges, against which the pointed guide-pin J will bear and exactly fit. This pattern j'' has the opening in which the guide-pin J travels like the recess in the saw-plate, the edges of which are to be milled or ribbed by the revolving and adjustable cutters d , and 75 by the motion and direction given to the pantograph guide-pin through the movement of the heads G and H by the operator by his manipulation of the hand-lever I by one hand and wheel h' with the other hand the guide-pin is made to traverse the inclined edge of the pattern j'' , giving direction to the revolving cutters d , so that these cutters will cut an angular or Δ -shaped rib on the edges of the recesses in the saw-plate that will exactly correspond with the form of the part of the pattern upon which the guide-pin travels. Other forms of the inwardly-projecting rib than a Δ or other angular shape may be made, as the milling-cutters d may be so formed as to 85 cut a circular, half-round, or conical-shaped rib just as well as the Δ shape, as the shape of the cutters gives shape to the rib. 90

I am aware that machines have been used for milling parts of sewing-machines, guns, 95 pistols, and other analogous things in which the pantograph movement, a guide and pattern working together to perfect forms are used; but such machines cannot be successfully used for cutting the ribs on the edges of a recess in a saw-plate for insertible or removable saw-teeth and their fastenings; and I do not claim, broadly, the movement of the pantograph and a pattern to direct the cutters except, as above described, in cutting the 100 inwardly-projecting rib in a recess of a saw-plate to receive an insertible tooth and its fastenings.

Having thus fully described my invention, what I claim, and desire to secure by Letters 110 Patent, is—

1. In a machine for milling the edges of the recesses in saw-plates to receive insertible teeth and their fastenings, the combination of the adjustable hand-lever I , toothed pinion i , rack i' , movable cross-head H , pantograph guide-pin J , pattern j'' , sliding head G , revolving shaft f''' , and gear-wheels g and g' , with the revolving cutters d , constructed and operating as described. 115

2. In a machine for milling the edges of recesses in saw-plates to receive insertible teeth and their fastenings, the combination of the movable and adjustable rest B , having plate B' , and clamping-screw a' , and carrying the 125 saw A , with the saw-clamping device D , substantially as described.

3. The clamping device D , composed of parts D' and D'' , having the clamping-jaws E attached thereto, and the means for adjusting one toward or from the other, substantially as 130 described.

4. In a machine for milling the edges of the recesses in saw-plates, the combination of the cross-head H, sliding head G, shafts F and f'', wheels g and g', revolving cutters d, pattern j'', pantograph guide-pin J, the movable rest B, carrying the saw-plate A, and clamping device D, substantially as described.

In testimony whereof I affix my signature in presence of two witnesses.

JAMES E. EMERSON.
